UNITED STATES PATENT OFFICE.

BERNARD SEELIG, OF NEW YORK, N. Y., ASSIGNOR OF ONE-HALF TO ELIAS ROTH.

SCRAPER ATTACHMENT.

1,390,168.

Specification of Letters Patent. Patented Sept. 6, 1921.

Application filed December 15, 1919. Serial No. 345,094.

To all whom it may concern:

Be it known that I, BERNARD SEELIG, a citizen of the United States, residing at New York city, borough of Manhattan, county and State of New York, have invented a certain new and useful Scraper Attachment, of which the following is a specification.

This invention is an attachment for scrapers and, more particularly, for those employed by painters and decorators.

It is the common practice when refinishing walls and ceilings, which have been previously calcimined, to remove the old calcimine before refinishing the surface, and in carrying out this practice the wall or ceiling is usually moistened and the old calcimine thereafter removed by means of hand scrapers. As this work has heretofore been carried out, flakes of calcimine have been allowed to fall on the floor or furniture in the room and water, with which the ceiling was previously moistened, was allowed to spatter with the result that it has been required to cover the floors and furniture with tarpaulins or canvas covers to preclude damage from the falling dirt and water. Moreover, when operating on ceilings the side walls have frequently been so badly marred as to require refinishing thereof.

The object of the present invention is to provide a hand scraper for carrying out these functions and others with an attachment, whereby the material scraped free from the surface is caught in the receptacle and is not allowed to fall broadcast throughout the room. The preferred embodiment of the invention contemplates an attachment which may be secured to any stock scraper in such manner that when the material is scraped free from a wall or ceiling it is caught in the receptacle which may be discharged from time to time as it becomes more or less full, into a convenient vessel such as a pail.

Features of the invention other than those specified, will be apparent from the herein-after detailed description taken in conjunction with the accompanying drawings.

In the accompanying drawings, I have illustrated one practical embodiment of the invention, but the construction therein shown is to be understood as illustrative only, and not as defining the limits of the invention.

Figure 1 is a perspective view showing a scraper with the attachment of the present invention associated therewith.

Fig. 2 is a perspective view of the attachment with the scraper removed; and,

Fig. 3 is a section on the line 3-3 of Fig. 1.

In the accompanying drawings, a well known style of stock scraper is shown embodying a blade 1 provided with the usual handle 2, and with this scraper is adapted to be associated the attachment 3 of the present invention, which is shown in Fig. 2. The attachment is preferably made from sheet metal and is in the form of a casing provided with an open end 4 and an open side 5. The open side of the casing 5 is adapted to be closed by the blade 1 of the scraper, and, accordingly, the longitudinal contour of the casing 3 is made to correspond to the shape of the blade, being tapered toward the base of the casing, as clearly shown in the drawings. Though not essential, the casing is, moreover, tapered in thickness toward the base thereof as this renders the attachment less bulky and cumbersome when attached to the scraper.

The edges of the casing adjacent the open side 5 thereof are provided with inwardly curved flanges 6 which extend from adjacent the open end 4 along said edges for the greater part of their length and directly adjacent the base of the casing, said edges are also provided with short flanges 6' formed in the same manner as the flanges 6, but intermediate the flanges 6 and 6', said edges are free from the flanges so as to enable the attachment to be positioned on or removed from the scraper. This is done by sliding the scraper relative to the attachment in a longitudinal direction toward the base of the casing 3 and causing the flanges 6' to snap over the blade 1 near the handle 2 as clearly shown in Fig. 1. Though it is not essential, the casing 3 may be provided with a handle member 7 which underlies a portion of the handle 2, as shown in Fig. 1. By providing the handle portion 7, the operator may by holding on to the handle 2, simultaneously hold on to the overlying portion 7 of the attachment so as to preclude any tendency of the attachment to work loose during use.

The flanged walls of the casing may be precluded from springing apart and releasing the attachment from the scraper during

use by means of spacing straps 8 and 9. Strap 8 extends across the open side of the casing near the open end thereof and overlies the blade 1 of the scraper, whereas the strap 9 extends across the open side about midway of the length of the attachment and is preferably curved longitudinally so as to allow of slight springing during the positioning of the attachment on or its removal from the scraper.

In employing a scraper to which the attachment of this invention is affixed, the scraper is manipulated in the usual way and as the particles of material are released from the surface operated upon they fall through the open end 4 into the casing 3 from which they may be dumped from time to time into a convenient pail or tub provided for this purpose. Experience has shown that old calcimine may be removed from the ceiling in a most cleanly manner and without depositing the removed material upon the floors or furniture. It is desirable that the casing be so formed that the walls of its open end project forwardly of the scraper in such manner as to catch the particles as they are released and fall, and said walls are preferably slightly flared at the open end to more efficiently carry out this purpose.

It will be understood that the specific invention described may be modified in formal respects, such as by the substitution of equivalents, and that parts of the complete mechanism described may be used alone, or in other environments, without departing from the spirit or substance of the broad invention, the scope of which is commensurate with the appended claims.

Having thus fully described the inven-

tion, what I claim as new and desire to secure by Letters Patent is:

1. An attachment for scrapers, having a blade and a handle therefor, embodying a casing provided with an open side and an open end, and flanges along the walls of the casing adjacent the open side thereof and adapted to resiliently engage with the lateral edges of the blade of the scraper to clamp said blade in position to close the open side of the casing and detachably mount the casing on the scraper, and a handle portion formed on the casing and positioned to underlie a portion of the handle of the scraper, so that the hand of an operator, grasping the scraper, will embrace the handle portion of the casing and maintain the casing against inadvertent disengagement from the scraper.

2. A scraper attachment embodying a tapered casing open at both ends and having an open side, flanges formed on the casing adjacent the open side thereof and adapted to engage with the lateral edges of a scraper blade, a nonyieldable tie member extending across the open side of the casing adjacent the larger end thereof for rendering the larger end of the casing rigid, and a yieldable tie member extending across the open side of the casing intermediate the ends of the casing to permit the flanges to resiliently grip the edges of the scraper blade and thereby detachably mount the casing on the scraper.

In testimony whereof, I have signed my name to this specification.

BERNARD SEELIG.

Witness:

ELIAS ROTH.
